TOBACCO PIPE

Samuel Lawrence Atkins, New York, N. Y.

Application July 14, 1945, Serial No. 605,137

5 Claims. (Cl. 131—198)

1

This invention comprises an improved tobacco pipe.

Among the objects of the invention are: To provide a pipe having a multi-section bowl and lead-out portion which can be readily taken apart to permit cleaning, repair or replacement of the parts; to provide a pipe having a bowl composed of upper and lower chambers separated by a removable grate for holding the tobacco particles in suspension, the grate (by virtue of its construction) affording complete combustion of the particles and permitting fresh air to be drawn into the lower chamber for mixing with the smoke, thereby reducing the temperature within the lower chamber; and to provide, for use in a pipe bowl, a removable grate having integrally arranged air inlets designed to fit into apertures in the bowl.

A more complete description of the invention follows in conjunction with a drawing, wherein:

Fig. 1 is a perspective view of a pipe constructed in accordance with the principles of the invention;

Fig. 2 is a longitudinal sectional view of the bowl and lead-out portion of Fig. 1;

Fig. 3 is a transverse section of Fig. 2 along the line 3—3;

Fig. 4 is a perspective view of a pipe bowl and lead-out portion of another embodiment of the invention;

Fig. 5 is a longitudinal sectional view of Fig. 4; and

Fig. 6 is a perspective view of the removable grate which is utilized in the bowls of Figs. 1 to 5.

Throughout the figures of the drawing, the same parts are designated by the same reference numerals.

Referring to Figs. 1, 2 and 3 in more detail, there is shown a tobacco pipe having a bowl or cup, a lead-out portion 14, 16, and a mouthpiece portion 20. The bowl or cup comprises an upper part 12 which has a bore 11 forming an upper chamber, and a lower part integral with the adjacent ends of lead-out portion or stem 14, 16 and forming a lower chamber 13. Chambers 11 and 13 are separated by a wire mesh grate 24 provided with tubular rods or inlets 26 having apertures 28 for permitting air to be drawn into the lower chamber.

The lower end of bowl portion 12 is cut away at 12' so as to nest into a shoulder 16' of the stem or lead-out portion. The cup or bowl of the pipe is formed of three sections 12, 14 and 16. These sections are held together by a re-

2

movable metallic band 18 which slides over the upper part 12.

The lead-out portion or stem, in effect, comprises two halves 14 and 16 which meet along line 17, and are provided with a central aperture or bore 15 which communicates at one end with the lower chamber 13 and at the other end with the conventional bore of the mouthpiece 20. One end of the lead-out portion or stem 14, 16 forms the lower end of the bowl, while the other end is tapered at 22 for nesting within the large dimensioned end 10 of the mouthpiece 20. Elements 14 and 16 are thus held firmly together by the band 18 at one end, and by the stem 20 at the other end.

The grate 24 is shown in more detail in Fig. 6, and comprises a central metallic wire mesh formation having a pair of square-shaped tubular rods or inlets 26 positioned opposite each other and securely fastened to said grate, as by soldering, brazing, etc. The tubular inlets are each provided with a central bore or aperture 28 for permitting air to be drawn therethrough. These inlets 26 are designed to fit into square-shaped apertures in portions 14 and 16 on opposite sides of lower chamber 13. The square configuration of the inlets 26 and the apertures in the lower part of the bowl or cup prevent rocking of the grate when positioned within the pipe bowl.

It should be noted from an inspection of Figs. 1 and 2 that the inlets 26 of grate 24 extend slightly beyond the exterior surface of the bowl and form a rest or stop for the band 18.

Figs. 4 and 5 illustrate another embodiment of the invention utilizing a bowl having upper and lower chambers 11 and 13 separated by a grate 24 provided with square shaped inlets 26. The essential difference between the embodiments of Figs. 4 and 5 and Figs. 1, 2 and 3 lies in the fact that the cup or bowl of Figs. 4 and 5 comprises only two parts 14a and 16a which form continuations of the lead-out portion or stem. Parts 14a and 16a constitute halves of the stem which meet along line 17a. The central or interior of the stem is provided with a bore 15a at the lower part of the bowl and this bore 15a communicates at one end with the lower chamber 13 of the bowl, as shown, and at the other end with the mouthpiece in the same manner as shown in Figs. 1 and 2.

In using the pipe of the invention, the inlets 26 permit air to be drawn into the lower chamber 13 by the draft or "pull" of the smoker on the pipe. This inrushing air mixes with the smoke in chamber 13 and reduces the temperature within

this chamber. The cooling of chamber 13 affects condensation of the tarry substances formed in the combustion of the tobacco and results in a dry smoke. The numerous openings in the grid-like grate enable the oxygen drawn into the lower chamber through inlets 26 to contact almost the entire surface of the tobacco resting on the grate, and thus achieve uniform and complete combustion of the tobacco particles.

The pipe of the invention is simple in construction, inexpensive to manufacture, efficient in use and service, and enables easy access to the different parts for cleaning, repair or replacement.

What is claimed is:

1. A tobacco pipe comprising a multi-section bowl having an upper chamber and a lower chamber, and a wire mesh grate separating said two chambers, said lower chamber communicating with the stem of the pipe, said grate having fixedly secured thereto solely at its edges a plurality of spaced tubular rods forming air inlets for said lower chamber, said bowl having a plurality of correspondingly spaced apertures extending from its interior at locations below the wire mesh portion of the grate to the outer surface of the bowl for accommodating the tubular rods of said grate.

2. A tobacco pipe comprising a multi-section bowl having an upper chamber and a lower chamber, and a wire mesh grate separating said two chambers, said lower chamber communicating with the stem of the pipe, said grate having fixedly secured thereto solely at its edges a plurality of square-shaped tubular rods forming air inlets for said lower chamber, said bowl having a plurality of square-shaped apertures corresponding in number and position to said rods for accommodating the same, and said apertures being located below the wire mesh portion of said grate.

3. A tobacco pipe comprising a multi-section bowl having an upper chamber and a lower chamber, and a foraminous grate separating said two chambers, said lower chamber communicating with the stem of the pipe, said grate having fixedly secured thereto solely at its edges on opposite sides thereof a pair of air inlet tubes for enabling air to be drawn into said lower chamber from outside of said pipe, and said lower chamber having

a pair of correspondingly positioned apertures for accommodating said air inlet tubes.

5. A tobacco pipe comprising a multi-section bowl having an upper chamber and a lower chamber, a wire mesh grate separating said two chambers, said lower chamber communicating with the stem of the pipe, said grate having fixedly secured thereto solely at its edges a plurality of spaced tubular rods forming air inlets for said lower chamber, and said bowl having a plurality of correspondingly spaced apertures extending from its interior at locations below the wire mesh portion of the grate to the outer surface of the bowl for accommodating the tubular rods of said grate, 10 and a metallic band encircling said bowl for holding the sections thereof together, said tubular rods extending past the outer surface of said bowl and forming supports for said metallic band.

5. A tobacco pipe comprising a multi-section 20 bowl having an upper chamber and a lower chamber, and a foraminous grate separating said two chambers, said lower chamber communicating with the stem of the pipe, and a pair of substantially diametrically positioned air inlet means 25 passing entirely through the walls of said pipe bowl and terminating at points adjacent the inner surfaces of the walls of said bowl and also adjacent but below the outer edges of said grate, said air inlet means having their axes in a plane 30 above said stem, said grate being supported in said bowl at its edges by said inlet means at points immediately above the inner terminations of said air inlet means.
